UNITED STATES PATENT OFFICE.

WILLIAM H. CLEMMANS, OF CAMDEN, NEW JERSEY.

GLARE-SHIELD FOR HEADLIGHTS.

1,325,619.

Specification of Letters Patent. Patented Dec. 23, 1919.

Application filed June 27, 1916; Serial No. 106,195. Renewed October 5, 1918. Serial No. 257,065.

To all whom it may concern:

Be it known that I, WILLIAM H. CLEMMANS, a citizen of the United States, residing at Camden, in the county of Camden and 5 State of New Jersey, have invented certain new and useful Improvements in Glare-Shields for Headlights; and I do hereby declare the following to be a full, clear, and exact description of the invention, such as 10 will enable others skilled in the art to which it appertains to make and use the same.

This invention has for its object to provide an improved shield or guard for headlights, which may be conveniently attached 15 to various modern types of motor vehicle headlights and will effectively protect the eyes of pedestrians against direct and glaring rays of light from the lamps.

Another object is the provision of means 20 for retaining the shield in position under the split ring of the lamp which is ordinarily utilized for supporting the lens in position.

With these and other objects in view, the 25 invention consists in the novel construction, combination and arrangement of parts as will be hereinafter specifically described, claimed and illustrated in the accompanying drawing, in which:

Figure 1 represents a side elevation of a 30 headlight, partly in section, illustrating the improved shield applied thereto,

Fig. 2 represents a front elevation of the 35 headlight and shield,

Fig. 3 represents a rear elevation of the 40 shield removed, and

Fig. 4 represents a transverse sectional view, on the line 4—4 of Fig. 3.

Referring to the drawing in detail, wherein similar reference numerals designate corresponding parts throughout the several views, the numeral 5 indicates the body of a well known type of electric headlight in which is supported the incandescent lamp 6. An annular lens supporting member 7 is 45 hingedly secured at 8 to the front open end of the body 5 and is formed centrally with a circumferential depression 9, providing an internal groove 10 in which is seated the lens 11. The lens is secured in the groove 50 10 against loose vibratory movement by an expanding split ring 12, which is seated in the groove 10 in front of the lens 11.

The improved shield or guard, designated by the numeral 13, is preferably constructed of sheet metal and the lower concave surface 55 14 thereof is highly polished so as to project the rays of light from the lamp 6 forwardly and downwardly from the headlight 5. The shield 13 extends across the upper half of 60 the lens 11 and is inclined forwardly and downwardly therefrom, as clearly shown in Fig. 1.

The rear edge of the shield is directed outwardly to present an angular retaining flange 15, which is positioned between the 65 wall of the groove 10 and the upper half of the retaining ring 12, to prevent vibratory movement of the shield with relation to the headlight. The end and central portions of the flange 15 are formed with lateral extensions, which are curved to provide a plurality of anchoring hooks 16 of such size as to partially embrace the ring 12 and prevent displacement of the shield due to excessive 70 vibration of the headlight and vehicle.

The shield is preferably constructed of relatively thin and flexible sheet metal, whereby it may be applied to the expansion ring 12 prior to the application of said ring to the lens supporting member 7, and, it is 75 clearly evident, that when the ring 12 is engaged in the groove the flange 15 of the shield is firmly clamped against the forward portion of the wall of the groove while the anchoring hooks 16 engaging between the 80 ring and the wall of the groove 10 rigidly secure the shield against vibratory movement or accidental displacement.

What I claim is:

1. In combination, a headlight including 90 a body, a lens supporting member carried by said body and having a circumferential depression providing an internal groove, a lens positioned in said groove, a split ring engaged in said groove and retaining said lens 95 in position, a glare shield including a curved body, an angularly directed flange carried by said body and engaged between said ring and the wall of said groove, and a plurality of anchoring hooks carried by said body and 100 partially embracing the upper portion of said ring and held between the latter and said lens supporting member.
2. In combination, a headlight including 105

a body, a lens supporting member carried by said body and having a circumferential depression providing an internal groove, a lens positioned in said groove, a split ring engaged in said groove and retaining said lens in position, a glare shield including a curved body, and a plurality of anchoring hooks carried by said body partially embracing the upper portion of said ring and

held between the latter and said lens supporting member.

In testimony whereof I affix my signature in presence of two witnesses.

WILLIAM H. CLEMMANS.
